UNITED STATES PATENT OFFICE.

LINCOLN BURNHAM, OF URBANA, OHIO.

METER.

1,338,852.

Specification of Letters Patent. Patented May 4, 1920.

Application filed October 31, 1918. Serial No. 260,437.

To all whom it may concern:

Be it known that I, LINCOLN BURNHAM, a citizen of the United States, residing at Urbana, in the county of Champaign and State of Ohio, have invented certain new and useful Improvements in Meters, of which the following is a specification.

This invention relates to improvements in meters, it being more particularly for metering water systems, and being especially of that type of meter employing a disk and known as a disk meter.

The object of the invention is to provide means for protecting the gearing which operates the registering device from the deteriorating action of the water by preventing the access of the water thereto.

In the accompanying drawings:

Figure 1 is a top plan view of the meter 20 with the protecting cover broken away.

Fig. 2 is a longitudinal section.

Referring to the drawings, 1 represents the main barrel or chamber through which the water or other fluid flows, 2 representing 25 the inlet and 3 the outlet. In this main chamber there is a bearing 4, centrally located therein by the webs 6, the webs being preferably formed in pairs and fitted together for the purpose of ready assembling 30 or removal.

Mounted in the bearing 4 is a ball 7 which has connected therewith a disk 8, the ball and disk being formed preferably of hard rubber. Also carried by the ball is a spindle 9. The construction so far described is 35 one which is in common use in meters of this character and the action of the water as it passes through the casing 1 is such as to impart to the spindle 9 a nutatory movement.

Clamped to the main casing 1 is a wall 10 having a centrally arranged beveled boss 11 which acts as a guide for the spindle 9 in its nutatory movement. The boss 11 is 45 chambered or hollowed out to receive packing 12 and a nut 13 to form a packing box. Journaled in the boss 11 and nut 13 is a shaft 14 having a right-angled extension 15 arranged in the path of movement of the 50 spindle 9 so that as the spindle nutates the shaft 14 will be revolved. This construc-

tion, with the exception of the division wall 10, is also old in meters of this character.

Connected to the shaft 14 is a worm 16 which meshes with the worm wheel 17 55 mounted in a bracket 18 on the upper side of the division wall 10. Eccentrically pivoted to the worm wheel 17 is a pawl lever 19 which coöperates with a ratchet wheel 20 mounted in a bracket 21 secured to the upper side of the division wall 10. This ratchet wheel 20 is operatively associated with a registering mechanism 22 of a well known form.

By the construction described it will be 65 seen that the gearing which operates the registering mechanism is separated from the water chamber 1 by the division wall 10 and by reason of the packing box described it is impossible for the water which passes 70 through the chamber 1 to come in contact with this gearing so that deterioration of the gearing by the action of the water thereon is prevented. The registering mechanism and gearing are preferably inclosed by 75 a cap 23, the cap 23, the division wall 10 and the main casing 1 being all connected together in any suitable way which will permit their ready separation.

Having thus described my invention, I 80 claim:

1. In a meter, a main open top chamber, a fluid chamber therein insertible through the open top thereof, a fluid operated member in said fluid chamber, a fluid tight cover 85 for the top of said main chamber, registering mechanism and operating devices therefor located on the top of said cover, an operative connection from said fluid operated member to said operating devices extending 90 through a fluid tight bearing in said cover, a casing for said mechanism and devices, and means common to the main chamber, cover and casing for clamping all three parts together.

2. In a meter, a main open-top chamber, a fluid chamber therein insertible through the open top thereof, a fluid operated member in said fluid chamber, a fluid-tight cover for the top of said main chamber and 100 secured thereto, said top contacting with the inner fluid chamber to hold the same

in position, a registering mechanism and its operating devices located directly on the top of said cover, a casing for said registering mechanism and operating devices, and an operative connection from said fluid operated member to said operating devices extending through a fluid tight bearing in said fluid tight cover, and means common

to the main chamber, cover and casing for clamping all three parts together.

In testimony whereof, I have hereunto set my hand this 29th day of October, 1918.

LINCOLN BURNHAM.

Witness:

CHAS. I. WELCH.
